UNITED STATES PATENT OFFICE.

SILAS HARRIS, OF SAN FRANCISCO, CALIFORNIA, ASSIGNOR TO THE PACIFIC ROLLING MILLS COMPANY, OF SAME PLACE.

RAILWAY-CHAIR.

SPECIFICATION forming part of Letters Patent No. 478,427, dated July 5, 1892.

Application filed October 16, 1891. Serial No. 408,922. (No model.)

To all whom it may concern:

Be it known that I, SILAS HARRIS, a citizen of the United States, residing in the city and county of San Francisco, State of California, 5 have invented certain new and useful Improvements in Railway-Chairs; and I hereby declare the following description and drawings accompanying and forming a part of the same to be a full and exact description of 10 my invention.

My invention relates to what are called "railway-chairs," employed to sustain and attach to the ties or sleepers railway-bars of T-section or other form having bottom flanges 15 for that purpose.

My invention consists in forming such railway-chairs from a single piece and of uniform section, except the top flanges, which are reinforced by being folded and welded together, 20 forming a double section of the bar at that point and providing more bearing and greater stability for clamping-bolts that hold and secure the rail, as will be hereinafter more fully explained in connection with the drawings, 25 in which—

Figure 1 is an elevation in perspective of one of my improved railway-chairs with a section of rail mounted thereon, showing, also, a portion of the sleeper or tie to which the 30 chair is fastened. Fig. 2 is an end view of the same chair, disclosing its transverse section, also showing more clearly the manner of attaching the rail thereto; and Fig. 3 is a plan of my improved railway-chair when detached.

Similar letters of reference on these different figures of the drawings are employed to indicate corresponding parts.

In the construction of railway-chairs it is 40 often desirable and preferable to fasten the rails by means of clamping-bolts, thus providing for convenient removal of the rails, and also to avoid bending clips or lugs made integral with the chair or fastened thereto, 45 which endangers fracture with any but the higher grades of metal.

Clamping-bolts inserted through the ordinary section or through a section strong enough for all other functions of the chair 50 are unstable under heavy strain, because of the thinness of the section they pass through. The strain upon such clamping-bolts is divided between these fulcrum—the pressure on the head at one side and pressure against the

upper and lower edges diagonally of the 55 hole through which they pass. So it follows that by increasing the distance between the two points last named by adding thickness correspondingly increases the strength of the clamping-bolts and the force with which they 60 may act. This is a principle of part of my invention, which I will now proceed to explain with the aid of the drawings. The chair is made from one piece of metal, the top flanges L L, bottom flanges M, and diagonal webs N 65 being formed integrally from a bar of uniform section, the top flanges being folded and welded together at O, where the clamp-bolts P pass through. As this welding at O constitutes the cross member Q a direct tie, mechanical joining of the vertical webs at R can be dispensed with; or in the case of heavy 70 service rivets can be inserted therein.

The clamp-bolts P P pass through a double thickness of metal, as shown in Figs. 1 and 2, 75 and are thus stiffened and supported against deflection by diagonal strain of the heads acting on one side only. The sleeper or ties S, rail T, and holding-down spikes V, being of the usual construction, do not require description here.

Having thus described the nature and objects of my invention, with the manner of constructing and applying the same, what I claim as new, and desire to secure by Letters Patent, is—

1. A railway-chair, as herein described, formed, primarily, of a bar having a uniform section, with top flanges L L folded and welded together so as to tie and support the vertical 90 webs N and reinforce the top flanges for clamping-screws P P, substantially in the manner and for the objects described.

2. In a railway-chair, as herein described, the diagonal web-plates N, abutting together 95 below the top flanges L L, the latter folded and welded to increase the thickness when the clamping-bolts P P pass through, in the manner described, substantially as and for the purposes specified.

In testimony whereof I have hereunto affixed my signature in the presence of two witnesses.

SILAS HARRIS.
